(57) **CLAIM**

We claim the ornamental design for a leak detection enclosure, as shown and described.

DESCRIPTION

FIG. 1 is a front perspective view of the leak detection enclosure comprising the present invention;

FIG. 2 is a front elevation view thereof;

FIG. 3 is a rear elevation view thereof;

FIG. 4 is a right side view thereof;

FIG. 5 is a left side view thereof;

FIG. 6 is a top view thereof; and

FIG. 7 is a bottom view thereof;

FIG. 8 is a front perspective view of the leak detection enclosure in an environment of use having light impinge from a first orientation as indicated;

FIG. 9 is a front perspective view of the leak detection enclosure in an environment of use having light impinge from a second orientation as indicated; and,

FIG. 10 is a front perspective view of the leak detection enclosure in an environment of use having light impinge from a third orientation as indicated.

Broken lines shown in the drawings illustrate portions of the leak detection enclosure and form no part of the claimed design.
